CLAIM

The ornamental design for a bag design, as shown and described.

DESCRIPTION

FIG. 1 is a perspective view of a bag design;

FIG. 2 is a front elevation view thereof;

FIG. 3 is a side elevation view thereof;

FIG. 4 top plan view thereof;

FIG. 5 is a bottom plan view thereof; and,

FIG. 6 is a perspective view showing the interior of the bag design.

The broken lines shown are included for the purpose of illustrating the unclaimed portions of the article and the article's environment and form no part of the claim.
